TYPE-WRITING MACHINE.

1,156,588.

Specification of Letters Patent. Patented Oct. 12, 1915.

Application filed August 26, 1910. Serial No. 579,078.

To all whom it may concern:

Be it known that I, DANIEL A. CARPENTER, citizen of the United States, and resident of the borough of Manhattan, city of New York, in the county of New York and State of New York, have invented certain new and useful Improvements in Type-Writing Machines, of which the following is a specification.

10 This invention relates particularly to improvements in carriage-arresting means which constitutes part of the tabulating mechanism of typewriting machines, and includes shock-absorbing means, the office of 15 which is to absorb the shock and safely distribute the stress, to which a machine is subjected when the carriage is arrested after it has run a long distance.

The object of the invention is to improve 20 the shock-absorbing means.

The invention consists of the mechanism which is hereinafter described and specified in the claims.

On the accompanying sheets of drawings, 25 on which like reference numerals designate like parts of different views, Figure 1 is a side and sectional elevation of parts of a Monarch typewriting machine embodying features of the invention; Fig. 2, a rear elevation of a portion of this machine; Fig. 3, a side and sectional elevation, on an enlarged scale, of parts of the tabulating mechanism; Fig. 4, a plan of a fragment of the machine; and Fig. 5, a broken plan and horizontal section of mechanism which includes a stop-bar and shock-absorbing springs.

The following description of the invention, it is believed, would enable a mechanic, skilled in the construction of typewriting 40 machines, readily to apply the invention to any of the well known type-bar machines, as well as to the Monarch whether the stop-bar of the tabulating mechanism is on the carriage or frame of the machine.

45 The drawings illustrate the invention embodied in column-jumping mechanism this mechanism being the only part of the Monarch machine represented herein in which that machine differs from a common Mon- 50 arch machine.

The frame of the machine is composed of the base 1, posts 2 and top-plate 3. The dog-rocker 4 is pivotally mounted in the hanger 5, attached to the top-plate, and is connected with the universal bar by the link 6, and 55 normally kept in the position in which it is shown in Fig. 1 by the spring 7. The escape-ment-wheel 8 is mounted on the shaft 9 which passes through the standard 10, affixed to the top-plate, and on this shaft, at its 60 front end, is the piston 11. The platen-frame, in which the platen 12 is mounted, is composed of the grooved rails 13 and 14 and end-plates 15, these rails and end-plates being a single casting and the rails being united by 65 a web 16 as well as by the end-plates. The feed-rack 17 is provided with arms 18 which extend between the rails 13 and 14 and are pivoted to the end plates 15 by pivots 19, and between each arm 18 and the rail 13 is a coil 70 spring 20 which bears downward on the arm. The platen-frame is connected by balls 21 and 22 with the grooved rails 23 and 24 which are affixed to the standards 25 and 26 that rest on and are attached to the top-plate 75 3. The tabulator-key, 27, is affixed to the rod 28, which is pivotally connected to the angular lever 29, this lever being mounted on the screw 30 by which the lever is attached to the lug 31 projecting from the rear post 2 80 at the right side of the frame. The link 32 connects this lever with the lever 33, which is pivoted by a screw 34 to a lug 35 formed on the under side of the top-plate, the lever 33 having on it a stop 36. The rack-lifter 37 85 is pivoted to and supported by the lever 33, the branches 38 extending on opposite sides of the bearing of the shaft 9 and being pro- 90 vided with shoes 39 which normally lie under and close to but not in contact with the rack 17. The push-bar 40, extending up- 95 ward from the rack-lifter and behind the rail 23, is riveted to the branches 38 of the rack-lifter, this push-bar comprising a yoke 41 which spans the bearing of the shaft 9. When the tabulator-key is actuated, this being done by pushing it inward, the rack 17 is raised by the rack-lifter out of engage- 100 ment with the pinion 11, the arms 18 of the rack turning on the pivots 19, so that then

the carriage is released from the control of the escapement-mechanism, and will be drawn to the left by the carriage-motor unless the carriage has previously reached the 5 end of its movement in that direction.

The carriage-arresting means, which forms part of the tabulating mechanism of this machine, comprises a stop-bar supported by arms which are affixed to the carriage 10 and in which the stop-bar is loosely mounted, a set of stops adjustably attached to the stop-bar, a combined stop and latch operative to engage a stop of said set and thereby to lock the stop-bar to the frame of the machine, when the carriage reaches a predetermined position in a tabulating operation, and a spring mounted on the stop-bar and forming a cushion, on which the carriage acts at the moment when the stop-bar is 15 locked to the frame, and which commonly will allow the carriage to pass that position, the spring being effective to return the carriage to that position. The stop-bar 42, illustrated in Figs. 1 *et seq.* to 4 inclusive, 20 extends through and fits loosely in the supporting arms 43 and 44 which are affixed to the back of the carriage, and on the bar at its ends are nuts 45 and 46. The collar 47 and volute spring 48 loosely surround the bar 25 between the arm 44 and the nut 46. This spring presses in opposite directions on the collar, and nut 46, keeping the collar in contact with the arm 44, and the spring normally keeps the nut 45 in contact with the 30 arm 43 (Fig. 4). The force exerted by this spring against the arm 44 is greater than that exerted by the carriage-motor on the carriage. This stop-bar is prevented from turning by means of the screw 49 set in the 35 arm 44 and extending into the slot 50 in the bar. The stop 51 attached to the bar 42 (Figs. 1 and 2) is the same as the column-stops which the Monarch machine has long contained, and this and other similar stops 40 forming a set fit in the slots in the stop-bar and are adjustable on the bar in the usual manner.

The combined stop and latch, above mentioned, are mounted in the supporting 45 bracket 52, which is fastened to the rail 23, this bracket having arms 53 and 54 in which the shaft 55 has bearings, and between 50 which the combined stop and latch 56 and 57 fit on the shaft, and by which they are held 55 close together and prevented from moving either to the right or left. The stop 56 is fastened to this shaft by the pin 58, and the spring 59, confined in the cavity 60 in the arm 54 and surrounding the shaft and 60 extending into holes in the stop and arm, normally keeps the arm 61 of the stop in contact with the back and top of the bracket 52, so that the stop then is out of the path of the stops 51 on the stop-bar. The arm 61 65 extends over the push-bar 40, whose upper

end fits loosely in the notch 62 formed in the under side of the arm. The latch 57 is attached loosely to the shaft 55 by the pin 63 which passes through the slot 64 in the hub of the latch and is fast in the shaft 70 (Fig. 4). The spring 65, surrounding the hub of the latch and bearing on the latch and the stop 56, normally keeps the front end of the slot 64, or that end which is shown in Fig. 4 above the other, in contact with the 75 pin 63. The projection 66 on the right side of the latch tapers on its under side 67 upward and backward from left to right. This latch, as well as the stop 56, is normally held out of the path of the stops 51 80 on the stop-bar. The arrangement of the parts of the carriage-arresting means is such that when the tabulator-key 27 is actuated as above described, the stop 56 is turned by the action of the push-bar 40 on the arm 61 85 of the stop to the position in which that stop is represented in Fig. 3, while the latch 57 turns with the stop 56 and at the end of their movement is in such a position that a stop 51 passing the latch from right to left 90 so acts on the tapered surface 67 as to force the latch backward against the action of the spring 65, far enough to enable the stop 51 to clear the latch and strike the stop 56. When a stop 51 thus passes the latch, the 95 spring 65 forces the latch behind that stop and then the stop which is attached to the stop-bar, and which cannot pass the stop 56, in confined between the latter stop and the latch so that the stop bar is locked to the 100 frame of the machine.

To predetermine the positions in which the carriage shall come to rest when its movements are controlled by the tabulating mechanism, the stops 51 are adjusted in the 105 usual manner on the stop-bar. Then, if a tabulating operation is performed, the predetermined position to be occupied by the carriage at the end of its movement, when it is to be restored to the control of the letter spacing mechanism, is that which the carriage will have reached, when the stop 51, which is to act on the stop 56, during that operation, shall make contact with the latter stop. But the carriage will pass this 110 predetermined position, if it has traveled more than a short distance, although the stop 51 and the stop-bar are arrested by the stop 56. As the carriage moves farther it acts on the spring 48, the arms 43 and 44 and collar 47 sliding on the stop-bar toward its left end, and the reaction of the spring on the carriage arrests the latter without subjecting the machine to any injurious shock or stress. The spring also 115 returns the carriage immediately after it is arrested to said predetermined position, for the force of this spring is greater than that exerted on the carriage by the carriage-motor, and any backward movement of the car- 120 125 130

riage beyond that position is prevented by the co-action of the latch 57, the stop 51, the stop-bar and the nut 45 on the arm 43. Then pressure is removed from the tabulator-key, whereupon the rack 17 reengages with the pinion 11 and the stop 56 and latch 57 return to their normal positions. Sometimes the carriage will be arrested, if it has traveled only a short distance, as soon as the stop 51 strikes the stop 56, the spring 48 being stiff enough then to prevent the carriage from going farther, but if the carriage travels beyond the predetermined position through any number of letter spaces, 15 or any fraction of a letter space, the spring will return the carriage instantly to that position.

Preferably provision should be made for the travel of the carriage through at least 20 two or three letter spaces, as indicated by the drawings.

The volute spring 48 is preferred to a common helical spring which might be substituted for it, because the resistance of the 25 volute spring increases, and the force of its re-action diminishes, so fast as to render it apt more gently to arrest and repel the carriage than would the helical spring.

Although the carriage-arresting mechanism above described illustrates features of the invention and their operation, yet it does not fully represent it. The arm 43 of a long or heavy carriage would be liable to strike the nut 45 rather hard, for a spring 35 48, strong enough to arrest the carriage after it had run a long distance, would force it back, frequently, with considerable violence. If, however, the stop-bar represented in Fig. 5 is substituted for that shown 40 in the other views, then the mechanism will gently arrest not only the forward but also the backward movement of a carriage. The stop-bar 68 (Fig. 5) is provided with notches in which fit adjustable stops 51, and 45 extends loosely through arms 69 and 70, and through bushings 71 and 72 screwed into hubs 73 and 74 formed on these arms, which correspond to the arms 43 and 44 above described, and are fast on the carriage. This 50 stop-bar has two oppositely facing shoulders 75 and 76 from which project parts 77 and 78 of the bar, the diameter of these parts being less than that of the part between the shoulders, and on the parts 77 and 78 are nuts 79 and 80, loose collars 81 and 82, and volute springs 83 and 84, the springs bearing against the collars and nuts, and normally keeping the collars in contact with the shoulders 75 and 76. The bushings 71 55 and 72 are to be adjusted so that the distance between the planes of their outer ends or faces will equal the distance between the planes of the shoulders 75 and 76, and consequently so that the collars 81 and 82 will normally rest against the bushings as well 60 as the shoulders. The screw 85, extending through a hole in the arm 70 and into the slot 86 in the bar 68, prevents the bar from turning but allows it or the carriage to be moved horizontally either to the left or 70 right although the other is held fast. This bar is so made and connected with the arms 69 and 70 that if the bar is moved endwise while the carriage is kept at rest, it will be restored to its normal position either by the 75 spring 83 or the spring 84, and that if the bar is held still and the carriage is forced to the right or left, one of these springs will return the carriage to the position from 80 which it was moved.

Now, it will be understood, when a tabulating operation is performed, the tabulating mechanism of the machine comprising the stop bar 68 and all of the other mechanism shown, except the stop bar 42, that the stop 85 bar 68 will be locked to the frame as soon as the stop 51, which acts in that operation on the stop 56, passes the latch 57; that the carriage will be arrested by the spring 84, the arms 69 and 70, and bushings 71 and 72, 90 sliding to the left on the stop bar, and the collar 82 being driven by the bushing 72 toward the nut 80, and the collar 81 remaining at rest and in contact with the shoulder 75; and that afterward the carriage will be 95 forced back by the spring 84 until the bushing 71 strikes the collar 81 and the collar 82 strikes the shoulder 76. If the bushing 71 strikes the collar 81 hard the shock will be transmitted to the spring 83, which will 100 gently arrest the backward movement of the carriage, and then, if the carriage shall have passed the predetermined position in which it is desired to have it come to rest, the combined action of the spring 83 and the carriage motor will return the carriage to that 105 position, which it will reach when the bushing 72 and collar 81 again make contact respectively with the collar 82 and the shoulder 75. When the carriage drives the bushing 71 against the collar 81 with less force than that which the spring 83 exerts on the collar, then the backward movement of the carriage will be arrested as soon as the bushing strikes the collar, so that in operations 110 wherein the carriage runs only short distances, the action of the collar 81, spring 83 and nut 79 is substantially the same as that of the nut 45 shown in Fig. 4. The force exerted by the spring 84 must be greater 115 than that exerted by the carriage motor, but the spring 83, whose action is aided by that of the motor, may exert either more or less force than does the motor. These springs are preferably volute springs, their action being 120 better than that of helical springs would be for reasons above stated. The stop bar 68 can be adjusted longitudinally by turning the bushings 71 and 72 so as to move them 125 equally in the same direction.

It is to be understood that the invention claimed could be embodied in mechanism differing in form and details of construction from that which has been specifically described above.

What I claim as new and desire to secure by Letters Patent, is:—

1. In a typewriting machine comprising tabulating mechanism, the combination in 10 the tabulating mechanism of a stop-bar movable endwise to change its position on its support, the bar being thus movable in both directions from the position which it naturally occupies on its support, and automatic 15 restoring means tending to prevent such a movement of the bar in either direction and operative on the bar when it is thus moved in either direction to force it back to its natural position on its support.
2. In a typewriting machine comprising tabulating mechanism, the combination in 20 the tabulating mechanism of a stop-bar movable endwise to change its position on its support, the bar being thus movable in both 25 directions from the position which it naturally occupies on its support, and automatic restoring means tending to prevent such a movement of the bar in either direction and operative on the bar when it is thus moved 30 in either direction to force it back to its natural position on its support, said restoring means including a pair of springs.
3. In a typewriting machine comprising tabulating mechanism, the combination in 35 the tabulating mechanism of a stop-bar movable endwise to change its position on its support, the bar being thus movable in both directions from the position which it naturally occupies on its support, and automatic 40 restoring means tending to prevent such a movement of the bar in either direction and operative on the bar when it is thus moved in either direction to force it back to its natural position on its support, said restoring 45 means including a pair of volute springs.
4. In a typewriting machine, a stop-bar movable endwise on its support in both directions from its normal position thereon, 50 in combination with automatic restoring means and adjusting devices.
5. In a typewriting machine, a stop-bar loosely mounted on its support and having two oppositely-facing shoulders, combined 55 with collars fitting loosely on the bar and normally resting against said shoulders and against surfaces of said support, and with cushions bearing against the collars and tending to keep them in contact with said shoulders and surfaces.
6. In a typewriting machine, a stop-bar loosely mounted on its support and having two oppositely-facing shoulders, combined 60 with collars fitting loosely on the bar and

normally resting against said shoulders, adjustable devices attached to said support and having surfaces with which said collars normally make contact, and cushions confined between said collars and holding-devices on the bar, the cushions tending to keep 65 the collars in contact with said shoulders and adjustable devices.

7. In a typewriting machine, a stop-bar loosely mounted on its support and having two oppositely-facing shoulders, combined 75 with collars fitting loosely on the bar and normally resting against said shoulders and against surfaces of said support, and with springs mounted on the stop-bar and bearing against the collars and tending to keep 80 them in contact with said shoulders and surfaces.

8. In a typewriting machine, a stop-bar loosely mounted on its support and having two oppositely-facing shoulders, combined 85 with collars fitting loosely on the bar and normally resting against said shoulders and against surfaces of said support, and with volute springs mounted on the stop-bar and bearing against the collars and tending to 90 keep them in contact with said shoulders and surfaces.

9. In a typewriting machine, a stop-bar loosely mounted on its support and having two oppositely-facing shoulders, combined 95 with collars fitting loosely on the bar and normally resting against said shoulders, adjustable devices attached to said support and having surfaces with which said collars normally make contact, and springs confined 100 between said collars and holding-devices on the bar, the springs tending to keep the collars in contact with said shoulders and adjustable devices.

10. In a typewriting machine, a stop-bar 105 loosely mounted on its support and having two oppositely-facing shoulders, combined with collars fitting loosely on the bar and normally resting against said shoulders, adjustable devices attached to said support and 110 having surfaces with which said collars normally make contact, and volute springs confined between said collars and holding-devices on the bar, the springs tending to keep the collars in contact with said shoulders and adjustable devices.

11. In a typewriting machine, a stop-bar mounted on the carriage and movable endwise on its support in both directions from its normal position thereon, in combination 120 with automatic restoring means, and means for locking the stop-bar to the frame when the carriage reaches a predetermined position in a tabulating operation.

12. In a typewriting machine, a stop-bar 125 mounted on the carriage and movable endwise on its support in both directions from its normal position thereon, in combination

with automatic restoring means and adjusting devices, and means for locking the stop bar to the frame when the carriage reaches a predetermined position in a tabulating operation.

5 Signed at the borough of Manhattan, city of New York, in the county of New York,

and State of New York, this 25th day of August, A. D. 1910.

DANIEL A. CARPENTER.
